UNITED STATES PATENT OFFICE.

SERN P. WATT, OF CHICAGO, ILLINOIS.

DESIGN FOR A GAS-LAMP.

SPECIFICATION forming part of Design No. 31,626, dated October 10, 1899.

Application filed September 11, 1899. Serial No. 730,176. Term of patent 7 years.

To all whom it may concern:

Be it known that I, SERN P. WATT, a citizen of the United States, residing at Chicago, in the county of Cook and State of Illinois, have invented and produced a new and useful Design for Gas-Lamps, of which the following is a specification.

In the drawings, Figure 1 is a side elevation of my gas-lamp; Fig. 2, a plan view thereof, and Fig. 3 a front elevation thereof.

In the accompanying drawings the vertical casing contains the carbid-chamber and the water-chamber arranged thereabove. The lower portion A of the casing is cylindrical, so as to form a cylindrical carbid-chamber closed at the bottom by a cap B and also to form the lower part of the water-chamber. The upper portion C of the water-chamber is rounding, being substantially elliptical in cross-section, with its greatest diameter somewhat more than that of the cylindrical part below. The water-chamber has projecting through its top the end of a valve-stem D, and such chamber is also provided with a water-inlet E for the admission of water into the water-chamber.

The flame-chamber F is bowl-shaped, with

a front glass or lens G and side jewels or lenses H. This flame-chamber is secured to a band J, extending around the cylindrical portion 30 of the casing and whose free ends form the lamp-bracket K.

An outlet pipe or passage L, governed by a valve M, leads from the front side of the carbid-chamber into the flame-chamber, where 35 it is provided with the burner or tip N. A curved or humped hood O is arranged on the flame-chamber above an opening in the flame-chamber directly over the burner.

The whole arrangement and relation of the 40 parts above described present an attractive appearance and give a pleasing effect to the eye of the observer and one that is harmonious and at once distinctive.

In the design of my lamp the lines of utility 45 are combined with and correspond to the lines of beauty.

I claim—

The design for a gas-lamp substantially as herein shown and described.

SERN P. WATT.
